brushes 1 and 2, 2 and 3, and 3 and 4, with the employment of only one generator.

Between each pair of brushes as aforesaid I place a pair of exploring or potentiometer contacts 8, 9 and 10 for very accurately detecting any variation in voltage drop in the small sections of the rail between the members of each pair of contacts. These contacts may be in the form of small copper brushes 73 and 74 or small wheels 75 and 76 as shown in Figs. 9 and 10. Said wheels are shown as mounted on pivoted arms 77, 77' pressed against the rail by springs 78'. The small wheels or trolleys have the advantage over the sliding brushes that they do not become heated at their points of contact with the rail as do the brushes. Such heating should be avoided in a sensitive thermionic system of this kind since it may generate thermo-couples in the system which would disturb the accuracy of the indicator. Current is lead to the wheels by brushes 79. The entire set of brushes both large and small may be mounted on a common frame 10' which may be raised and lowered by any suitable means such as a crank handle 11 mounted on a shaft 12 which has worms 13 and 14 thereon geared to worm wheels 15. Said wheels are each provided with an arm 16 engaging parallel linkage 17 of frame 10' so that the brushes may be raised and lowered by rotating the crank 11. Preferably also the same crank serves to raise and lower a pair of stiff, revolving brushes 18, 19 for cleaning the rail when the device is in operation, said brushes being shown as revolved from the axle 20 of the car wheels 21 as by means of a pinion 22 and gear 23.

Fig. 3 represents a preferred means for amplifying the variation in voltage drop between the members of the pairs of contacts 8 when a flaw is passed over. Said contacts are placed in electrical relation with a cascade amplifying system 24 of the thermionic direct current type in which the contacts are placed so as to charge the grid 25 of No. 1 tube 26 with a (say) negative potential, the variations in the potential of the grid of this tube relative to the filament 27 governing the other tubes of the amplifying system. The more negative the grid potential becomes with respect to the filament, the lower the output of the amplifier.

If, however, no further means is employed, the output of the system will increase to a very large figure if the contact between the brushes 8 and the rail becomes poor, or in case the brushes 8 bounce off the rail, thereby reducing the negative potential to zero. To correct this difficulty a resistance 28, on the order of 100,000 ohms or more, is inserted across the brushes 8 and a variable potentiometer 29 is provided which may be adjusted to give a predetermined output for the difference in potential drop due to the

potentiometer and that due to the rail between the brushes 8. If any flaw is encountered the loss of potential at the rail increases and, therefore, the difference between the potential drop (E_1) of the potentiometer and rail (E_2) becomes smaller so that the output increases to actuate the indicator, but if the brushes bounce from the rail or bad contact is encountered, the drop (E_2) at the rail becomes or approaches zero, and, therefore, the total potential ($E_1 - E_2$) increases and the output drops toward or to zero, resulting in no indication or at least an indication of a different character from that caused by a flaw.

Preferably also separate "B" batteries are provided for some or all of the tubes. If, for instance, the same "B" battery 31 were used for the last tube 30 as for the others any increase in flow of current therethrough would cause a drop in voltage of the B battery and, therefore, a drop in voltage supplied to the plates of other tubes resulting in the rapid building up of an unstable condition. With a separate "B" battery 31' and 32 for the other tubes, this trouble is avoided. Each unit of the amplifying system is preferably shielded as by metallic coverings 80, such covering also extending to the wires leading to the brushes 8, 9 and 10, as indicated at 81 and to the batteries 31 and 31', so that outside electrical influences are carefully excluded.

The last tube is connected directly or indirectly to some form of indicating mechanism 33. As shown it is connected to a winding 34 on a marker mechanism which gives an indication on a traveling chart 35 when a flaw is encountered. The chart is shown as continuously actuated from the car wheels as by means of bevel gearing 36 and a sprocket and chain 37. Each pen or marker mechanism is shown as comprising a U-shaped magnet 38 (Figs. 5 and 6), a magnetizing coil 39 which may have current continuously supplied thereto, and said coil 34 in circuit with or controlled by the amplifying system.

An armature in the form of a spring plate 41 pinned at its base projects through said last-named coil and up between the ends of said U-shaped magnet, the armature being preferably of soft iron and having a pin 42 engaging a slot 43 in the reed 44 which holds the pen 45. Said pen is shown as dipping at one end 46 into an inkwell 47 and at the other end 48 as bearing on the chart 35. As the winding 34 is excited the soft iron armature becomes polarized and is pulled towards one pole or the other of the permanent magnet as will be readily apparent, with a force proportional to the current flowing and against the spring bias of the plate 41, which is represented in Fig. 8 by spring 41'.

As explained above, if a flaw is encountered, the pen will be pulled in one direction

to cause mark 51, and if bad contact is encountered or the potentiometer brushes bounce from the rail, the pens will be pulled in the opposite direction to cause marks 90, 90' and 90'' as the current through coil 34 will then decrease instead of increase.

The pen will also be actuated at each rail joint as shown at 53, 53' and 53'', but the rail joints will actuate the pens to a much greater extent than the flaws and also be more sharply defined, so that their markings may be readily distinguished from those caused by flaws on the chart. It will be understood that each set of brushes 8, 9 and 10 is connected to a separate amplifying system 24 and pen so that as shown there are three pens 45, 45' and 45'' for each rail, each pen tracing a separate line 50, 50' and 50'' on the chart and giving an indication 51, 51' and 51'' of the flaw as the connected pair of brushes pass over the same. This not only gives a triple check on the flaw but also furnishes an additional means for distinguishing between a flaw and a case where the entire brush system 1, 2, 3 and 4 bounces off the rail, the case of non-contact with the rail, above considered, being where the detecting brushes 8, 9 or 10 lose contact successively with the rail. The pens may be so arranged on the chart in staggered relation, as shown in Fig. 1, that for a flaw or bad contact spot the markings 51, 51' and 51'' or 90, 90' and 90'' on the chart appear in the same straight line across the same (Fig. 4). Where, however, the entire brush mechanism is bounced off the rail, the markings of the pen will be in staggered relation 52, 52' and 52'', the three pens marking simultaneously but the markings appearing in staggered relation as the brushes are placed in staggered relation on the chart. The record C for rail R is shown on the left hand side of Fig. 4 and the record C' for the rail R' on the right hand side, the pens being shown as moved oppositely in the two instances. A flaw appears at 151 on record C'.

In addition to or instead of making a record of the flaws, I may provide other signalling means. In Fig. 8, for instance, I have shown both a means for giving an audible signal when a flaw is encountered and also a means for marking a defective rail at a point near the flaw. In this figure the pen mechanism is again shown at 33. An extra contact 55 is provided thereon which is so spaced as normally not to be closed by ordinary flaws, but which is closed by the greater effect caused by the rail joint. As the pen moves in the opposite direction, when contact is lost or poor, said contact and also contact 62 (hereinafter described) are not closed under such conditions. When closed said contact excites a relay coil 56 which controls an armature 57 having two sets of contacts 58 and 59. The upper contact 58 is closed by excitation of said coil 56 and is in circuit with a

counter 60 or the like which counts the rail joints so that the defective rail may be located by counting the number of rails from a given point. Said contacts 58, however, are normally maintained open by a spring 60' and dashpot 61. The back contacts 59 are in circuit with another pair of contacts 62 which is controlled by the relay coil 34' of the second or third pair of brushes 9 or 10. This set of contacts when closed at the time the first set is closed will actuate the loud-speaker 63 and preferably also the rail-marking device 64. From this it will be seen that for an ordinary flaw the loud-speaker and marking-device will be operated because both the contacts 62 and 59 will be closed, since contact 55 is not closed, by reason of the insufficient movement of the pen. However, for rail joints, since contact 55 is closed, the loud-speaker will not be operated as when contact 55 is closed the back contacts at 59 will be open, and the contacts 58 through the counter 60 be closed. For bad contact conditions, also, no operation will occur as both contacts 55 and 62 remain open.

As shown, the rail-marking device is in the form of a paint-daubing device. Paint is placed in the container 66 to which is connected a source of compressed air through the pipe 67. A valve 68 is placed in the outlet pipe 69 which is normally maintained closed but which is opened by means of an electro-magnet or solenoid 70 connected to the slide valve 68, so that when the electro-magnet is excited, the valve will be momentarily opened and a splotch of paint splashed on the rail, the valve being closed again by spring 71.

Other forms of amplification may obviously be used for amplifying the feeble variations in voltage drop at the relay to actuate the indicator or signal. In Fig. 11 I have shown a transformer type of radio amplifier as distinguished from the non-inductive type, such as shown in Fig. 3. According to this modification, a means is interposed for introducing a high frequency interruption of the primary circuit to render the use of the transformer type feasible. Such an interrupter is indicated at 91 and comprises an armature 92 normally biased to close back contacts 93 by means of the spring 94. A coil 95 in circuit with switch 93 attracts the armature 92 to close contacts 96, which is in the primary circuit. It will be understood that this contact device will vibrate rapidly to make and break the primary circuit. In said circuit is placed a transformer 97, the secondary being connected to the grid 25' of the first tube 26'. From this point on any number of stages may be added as indicated by the transformer 97' and tube 30', the last tube having its plate 98 in circuit with the relay 33 as in the system described in connection with Fig. 3. It will be understood that in such a system the "C" battery 99 is adjust-

ed to give a bias on the grid 25" of the last tube such that the relay only operates with a greater than normal variation due to the rail flaw or the like.

5. The operation of the hereinbefore described application of my invention is as follows:

The rail car is moved at a moderate rate of speed along the track under test by which the cleaning brushes are revolved. The contact 10 brushes are kept in contact with the rail during the test but may be raised when passing over switches, cross-overs, and the like. As each rail joint is passed over three mark 53, 53' and 53" are made on the chart and if a 15 flaw is passed over three markings of a different character 51, 51', and 51" are made, and at the same time the alarm 63 is sounded and a paint mark made on the rail. As explained above, poor contact spots on the rail 20 or bouncing of the brush system off the rail, make markings of a different character on the chart, and do not actuate the alarm or rail marker. Also I prefer to employ means in the 25 amplifier circuit, such as condenser 98' shunted around resistance 99 to suppress oscillations of radio frequency so that only oscillations of much less frequency, such as occasioned by rail flaws, reach relay 33.

In accordance with the provisions of the 30 patent statutes, I have herein described the principle and operation of my invention, together with the apparatus which I now consider to represent the best embodiment thereof, but I desire to have it understood that the 35 apparatus shown is only illustrative and that the invention can be carried out by other means. Also, while it is designed to use the various features and elements in the combination and relations described, some of these 40 may be altered and others omitted without interfering with the more general results outlined, and the invention extends to such use.

Having described my invention, what I 45 claim and desire to secure by Letters Patent is:

1. A rail flaw detector comprising a plurality of spaced contacts, means for moving relatively said contact and rail, means for supplying electric current to the rail, a pair 50 of contacts between said first-named contacts, means for detecting variations in the voltage drop therebetween, means for amplifying such variation, and rail-marking means actuated therefrom to place a mark on the rail adjacent each flaw.

2. A rail flaw detector comprising a plurality of spaced contacts means for moving relatively said contact and rail, means for 55 supplying electric current to the rail, a pair of contacts between said first-named contacts, means for detecting variations in the voltage drop therebetween, means for amplifying such variation, an indicator operated 60 therefrom, and means for preventing opera-

tion of said indicator by rail joints, loss of proper rail contact and the like.

3. In a rail flaw detector, a source of current, means movable along the rail for passing current through the rail between spaced 70 points, detector means also movable with said first means and responsive to variations in the characteristics of current flow, rail-marking means actuated therefrom to place a mark on the rail adjacent each flaw, and 75 means for preventing actuation of said rail-marking means by rail joints.

4. A rail flaw detector comprising a plurality of spaced contacts adapted to be moved along the rail, means for supplying electric 80 current thereto, a pair of contacts between said first-named contacts, means for detecting variations in the voltage drop therebetween, means for amplifying such variation, rail-marking means actuated therefrom to place a mark on the rail adjacent each flaw, and means for preventing actuation of said marking means by poor contact conditions between said contacts and the rail.

5. A rail flaw detector comprising a plurality of spaced brushes adapted to be moved along the rail, means for supplying electric current thereto, a pair of contacts between said brushes, means oppositely responsive to variations in the voltage drop due to flaws in the rail and those due to loss of electrical contact with said rail by said contacts, said last-named means comprising opposed potentiometers, one of said potentiometers being connected to said contacts, the other of said potentiometers being connected to a source of E. M. F. of known strength, means for amplifying the differential of said potentiometers, indicating means, and means whereby said indicating means is actuated in one direction or the other according as said differential is greater or less than a predetermined normal differential.

6. A rail flaw detector comprising a plurality of spaced brushes adapted to be moved along the rail, means for supplying heavy current thereto, a pair of contacts between said brushes, means responsive to variations in voltage drop between said contacts due to flaws in the rail, means responsive to greater variations in voltage drop due to rail joints, indicating means adapted to be actuated by said first responsive means, and means whereby said indicating means is rendered ineffective when said second responsive means is rendered effective.

7. A rail flaw detector comprising a plurality of spaced brushes adapted to be moved along the rail, means for supplying heavy current thereto, a pair of contacts between said brushes, means responsive to variations in voltage drop between said contacts due to flaws in the rail, means responsive to greater variations in voltage drop due to rail joints, indicating means, means including electrical 120

switch means whereby said first responsive means actuates said indicating means, and means whereby said switch means and said indicating means are rendered ineffective 5 when said second responsive means is rendered effective.

8. In a rail flaw detector, a source of current, means movable along the rail for passing current through the rail between spaced 10 points, detector means also movable with said first means and responsive to variations in the characteristics of current flow, and rail marking means actuated therefrom to place a mark on the rail adjacent each flaw.

15 In testimony whereof I have affixed my signature.

HARCOURT C. DRAKE.
